UNITED STATES PATENT OFFICE.

ROBERT PRICE STRACHAN AND GEORGE HENSHAW, OF LONG ROW,
VICTORIA STREET, BRISTOL, ENGLAND.

CARD-SCORING MACHINE.

SPECIFICATION forming part of Letters Patent No. 289,162, dated November 27, 1883.

Application filed November 22, 1881. (No model.)

To all whom it may concern:

Be it known that we, ROBERT PRICE STRACHAN and GEORGE HENSHAW, subjects of the Queen of Great Britain, residing at Long Row, 5 Victoria Street, Bristol, England, have invented certain new and useful improvements in machinery or apparatus for scoring or partially indenting or cutting through cards or thick papers, to facilitate their being folded or bent, 10 of which the following is a specification.

This invention relates to new or improved arrangements and combinations of mechanism or apparatus for scoring or partially indenting or cutting through cards or thick papers, 15 to facilitate their being folded or bent; and in order that our invention may be clearly understood and readily carried into practice, we will proceed to describe the drawings hereto annexed.

20 The machine or apparatus consists of a flat plate, bed, or slab, A, Figures 1, 2, and 3, made of iron, marble, or other suitable material, above which is fixed a bar, B, parallel to the surface of the plate A. On this bar B slides 25 a cutter slide or block, C, carrying one or more knives or circular rotating cutters, D, which cutters can be adjusted for distance from the plate A or from each other. The head of the 30 plate A of the machine is provided with a ledge or fence, E, against which the card can butt, and an adjustable side lay, F, is also provided, against which the side of the card may be set. The ledge E and the lay F constitute gages, and the latter is fastened to the plate or 35 bed A by a thumb-screw, o, passing through a slot, o', whereby provision for its adjustment is afforded.

The operation of the machine is as follows: The card or other material to be scored is placed 40 on the plate or bed A and adjusted by the head-ledge E and side lay, F, and, being held by the hand of the operator, or by other suitable means, the block, with its cutter, is passed over it, scoring the card to the depth to which the cutters are adjusted. By means of the head- 45 fence and side lay accuracy of position of the scoring is insured.

The knife may be formed of a piece of steel having a spring or resilient shank fastened by

one screw, and adjusted by another screw, s', 50 the knife returning and keeping firmly against the screw s' by its own elasticity, as shown at Figs. 4, 5, 6.

Figs. 1, 2, 3, and 7 illustrate an ordinary scorer worked by hand by means of the knob 55 a. Figs. 5 and 6 illustrate a scoring-machine in which are employed several cutters. In these figures the slide C is represented as carrying a cross rod or bar, b, on which are adjustably secured blocks c, which carry cutters 60 D. Figs. 8 and 9 illustrate machines adapted to be operated by the foot of the workman, or by other motive power, by means of pulleys.

In Fig. 8 the cutter-slide C is connected by a rod, d, with one end of a lever, G, fulcrumed 65 at d', and the opposite end of said lever is connected by a rod, d', with an arm, d'', projecting upward from a treadle, H, which is fulcrumed at d''. By depressing the treadle H by the foot the slide C is moved toward the left 70 hand, and the treadle is returned, after depression, by either a spring, e, or a counterbalance-weight, e', both of which are here represented.

In Fig. 9 we have represented a rotary shaft, f, carrying a fly-wheel, f', and which is operated by a treadle, H, through a rod, f''. G designates a lever fulcrumed at g, and connected with the cutter-slide C by a rod, g'. The 75 said lever is vibrated by a rod, g'', which receives motion from a crank on the far end of the shaft f. The shaft f might be rotated by a belt passing round a pulley upon it.

Fig. 10 represents a side view and a transverse section of a segmental head-ledge, useful 80 in multiple scoring.

Fig. 11 illustrates an arrangement of rotary cutters applicable to our improved scoring-machines.

What we claim as our invention, and desire 85 to secure by Letters Patent, is—

1. The combination, with the cutter-slide C, of the cutter D, having a spring or resilient shank fixed to the slide, and the set-screw s', for adjusting said cutter, substantially as herein specified.

2. In a machine for scoring cards or paper, the combination, with a bed or plate and a guide or guides parallel therewith, of a slide

movable upon said guide or guides, a cross-bar carried by said slide, and two or more blocks adjustably secured upon said cross-bar, and each carrying a cutter, substantially as specified.

5. 3. The combination of the bed or plate A, the guide-bar B, the cutter or cutters D, the slide C, fitting said bar, and carrying the cutter or cutters, a lever, G, connected with said

slide, and devices for vibrating said lever, and thereby reciprocating said slide, substantially as herein specified.

ROBERT PRICE STRACHAN.
GEORGE HENSHAW.
